UNITED STATES PATENT OFFICE.

EARL N. STROUP, OF WEST VIEW, PENNSYLVANIA, ASSIGNOR OF ONE-HALF TO JAMES A. SKILES, OF PITTSBURGH, PENNSYLVANIA.

FEED-HOLDER.

1,144,157.

Specification of Letters Patent. Patented June 22, 1915.

Application filed September 14, 1914. Serial No. 861,493.

To all whom it may concern:

Be it known that I, EARL N. STROUP, a citizen of the United States, residing at West View, Allegheny county, Pennsylvania, have invented a new and useful Improvement in Feed-Holders, of which the following is a full, clear, and exact description, reference being had to the accompanying drawings, forming part of this specification, in which—

Figure 1 is a longitudinal section through one form of device embodying my invention. Fig. 2 is a perspective view of a hood or cover for the feed holder shown in Fig. 1.

This invention relates to an improvement in feed holders, and is more particularly designed for holding feed for poultry.

The object of my invention is to provide a holder of this character, which can be cheaply manufactured, and in which the feed, which is thrown by the poultry when feeding from the device, will be caught and retained in a reservoir.

The precise nature of my invention will be best understood by reference to the accompanying drawings, it being premised, however, that various changes may be made in the details of construction without departing from the spirit and scope of my invention, as defined in the appended claims.

Referring to the accompanying drawings, the reference character 2 designates a hollow base having a drawer 3, slidably mounted therein. Connected to the top of the hollow base and extending upwardly from an opening in the top thereof is a pan 4, which I have shown as flaring upwardly and outwardly. Mounted within the pan 4 is a feed

holder proper, which comprises the flanged plate or bottom 5 secured to the pan 4 by means of wings or clips 6, in such a manner that there is an open space between the pan 4 and the sides of the plate 5. Extending upwardly from the plate 5 is a column 7

which I have shown as flaring inwardly and having an outwardly flared cap 8 removably connected to its upper end, and pivotally connected to the cap 8 is a cover 9. The walls of the column 7 are provided with a plurality of perforations 10, and 11 is a hood or cover which is arranged to seal the openings 10 and the top of the pan 4 when the feed is not to be exposed, so as to prevent vermin from eating the feed. When

it is desired to place the cover 11 in position the cap 8 is removed and the cover 11 placed in position as shown in dotted lines in Fig. 1, the cap 8 being then placed in position on the top of the column 7.

The feed is poured into the cap 8 and drops into the column 7 which can be entirely filled and as the feed is exposed through the openings 10, the poultry can obtain it by pecking at these openings and some of the feed will also be exposed adjacent to the annular flange 5^a surrounding the plate 5. Any of the feed which falls from the openings will be caught by the pan 4 and will drop into the drawer 3. I prefer to make the drawer large enough to hold as much feed as the column 7, so that the drawer 3 and pan 4 will never be filled by the contents falling from the column 7. After the feed has all been consumed that has been placed in the column 7, the feed in the drawer is emptied into the column.

It will readily be understood by those familiar with the art, that a great deal of feed is saved by the use of a device of this character, as all of the feed which is thrown in a lateral direction by the poultry is caught by the pan 4 and deposited in the drawer.

It is well known to all poultrymen that when mixed feed is used, the poultry will pick out the feed that is most appetizing and waste the remainder if it is not caught up in a suitable device, but by using a device of this character, the feed which the poultry does not like is caught up in the drawer and can then be placed into the hopper and will be eaten by the poultry if the appetizing food is all gone.

The advantages of my invention result from the provision of a catch pan surrounding a feed device for catching and retaining the feed falling from the feed device.

I claim:

1. A feed holder having a hollow base, a feed column above the base and supported thereby, a plate connected to the lower end of the column and closing the bottom thereof, there being a plurality of openings through the wall of the column, the plate extending beyond the wall of the column and having an upwardly extending flange, a pan surrounding said plate and communicating with the hollow base, there being an an-

nular space between the edge of the flange on the plate and the pan, and a removable receptacle in the hollow base for catching feed which falls into the pan.

5. 2. A frusto-conical feed holder having a plurality of openings through the wall thereof adjacent to the lower end, a plate secured to the bottom of the column and extending beyond the edge thereof, said plate having 10 an upwardly extending annular flange, and a catch pan below and surrounding the plate; substantially as described.

3. A feed holder having a hollow base, a feed column above the base and supported thereby, said column having a plurality of openings through the wall thereof at the lower end, a plate connected to the lower end of the column and closing the bottom thereof, said plate extending beyond the wall of 20 the column and having an upwardly extending flange, a pan surrounding said plate and communicating with the hollow base, there being a space between the edge of the flange on the plate and the pan, substantially as 25 described.

4. A feed holder comprising a hollow base, an upwardly and outwardly flaring hopper connected to the base and communicating

therewith, a plate having an upwardly extending annular flange supported in the 30 hopper, there being an annular space between the annular flange and the hopper, a feed column supported on the plate, said column having a plurality of openings through the wall thereof at the lower end, 35 and a removable cover for closing the openings through the wall of the column and the top of the hopper, substantially as described.

5. A frusto-conical feed holder having a 40 plurality of openings through the wall thereof adjacent to the lower end, a plate secured to the bottom of the column and extending beyond the edge thereof, said plate having an upwardly extending annular flange, a 45 catch pan below and surrounding the plate, and a removable cover for closing the openings through the wall of the column and the top of the pan; substantially as described.

In testimony whereof, I have hereunto set 50 my hand.

EARL N. STROUP.
